UNITED STATES PATENT OFFICE.

THEODORE KIRCHEN, OF CHICAGO, ILLINOIS.

DESIGN FOR A HANGING ORNAMENT.

54,756.

Specification for Design.

Patented Mar. 23, 1920.

Application filed August 30, 1919. Serial No. 320,948. Term of patent 3½ years.

To all whom it may concern:

Be it known that I, THEODORE KIRCHEN, a citizen of the United States, residing at Chicago, in the county of Cook, State of Illinois, have invented a new, original, and ornamental Design for a Hanging Ornament, of which the following is a specification, reference being had to the accompanying drawing, in which a perspective view of the design is shown.

I claim:—

The ornamental design for a hanging ornament, as shown.

In testimony whereof I affix my signature.

THEODORE KIRCHEN.
